(57) **CLAIM**

The ornamental design for a plug seal, as shown and described.

DESCRIPTION

FIG. 1. is a perspective view of a plug seal showing the design;

FIG. 2. is a second perspective view thereof;

FIG. 3. is a top plan view thereof;

FIG. 4. is a bottom plan view thereof;

FIG. 5. is a left side elevation view thereof;

FIG. 6. is a right side elevation view thereof;

FIG. 7. is a front elevation view thereof;

FIG. 8. is a rear elevation view thereof;

FIG. 9. is a perspective view thereof, shown in an environment of use;

FIG. 10. is a perspective view of a second plug seal showing the design;

FIG. 11. is a second perspective view thereof;

FIG. 12. is a top plan view thereof;

FIG. 13. is a bottom plan view thereof;

FIG. 14. is a left side elevation view thereof;

FIG. 15. is a right side elevation view thereof;

FIG. 16. is a front elevation view thereof;

FIG. 17. is a rear elevation view thereof; and,

FIG. 18. is a perspective view thereof, shown in an environment of use.

The broken lines showing a bottle and tubing in FIGS. 9 and 18 illustrate environmental structure. All other broken lines illustrate portions of the plug seal. The broken lines form no part of the claimed design.

1 Claim, 18 Drawing Sheets
